UNITED STATES PATENT OFFICE.

JUSTUS CORNELIS ZUBLI AND ABRAHAM VLES, OF SEATTLE, WASHINGTON.

ATTACHMENT FOR ELECTRIC LIGHTS.

1,025,896.

Specification of Letters Patent.

Patented May 7, 1912.

Application filed August 2, 1909. Serial No. 510,917.

To all whom it may concern:

Be it known that we, JUSTUS CORNELIS ZUBLI and ABRAHAM VLES, subjects of the Queen of the Netherlands, residing in the 5 city of Seattle, county of King and State of Washington, have jointly invented a new and useful Attachment for Electric Lights, of which the following is a clear and concise specification.

10 The objects of our invention are to provide a dust proof reflector; to provide a plurality of triangular prisms so connected and secured to the reflector supporting the said prisms as to prevent the dust from accumulating 15 on the back of each of the prisms as well as on the face of the reflector; to provide a dust proof shade and reflector to increase the brilliancy and to show colored rays of light. We accomplish these as well 20 as minor objects by the construction now preferred by us and illustrated in the accompanying drawings, in which—

Figure 1 is the vertical section of the lamp shade reflector and prisms; Fig. 2 is 25 a front elevation of the preferred form of my device; Fig. 3 is a horizontal section of the prism showing how the prisms are connected to prevent dust from entering therebetween; Fig. 4 is a modification of our device in which we have provided a plurality 30 of colored lights surrounding the main light which colored lights take the place of the reflector as illustrated in the Figs. 1 and 2 and Figs. 5 and 6 are modifications of the 35 arrangement of the lights of our device.

Similar reference numerals refer to similar parts of our device illustrated in the several views of the accompanying drawings and hereinafter set forth.

40 Our invention consists essentially of an electric light globe 1 surrounded with a shade 2 which is provided with a plurality of colored reflectors 3 said reflectors preferably diverging from said electric light globe 45 1 and toward the end of the diaphragm 4 comprising the plurality of triangular prisms 5 connected by the transparent plate 6 formed integral therewith. Said diaphragm 4 is preferably provided with an 50 annular flange 7 which rests against the face of the flange 8 which is secured or formed integral with both the shade 2 and the plurality of reflectors 3. To secure said diaphragm 4 to said reflectors 3, we have provided 55 an annular metallic housing 9 which is provided with a hinge 10 at one side and

yielding catch 11 diametrically opposite the hinge. Said hinge 10 is secured to an annular frame piece 12 which frame piece 12 rests against one face of the flange 7 of said 60 diaphragm 4 thus holding the opposite face in contact with the flange 8, it being obvious that the housing 9 is prevented from movement by an annular depending flange 13 engaging the back of the flange 8.

65 Some of the rays of light from the lamp 1 strike the colored reflecting planes 3 which in turn direct the rays into the prism 5 giving pleasing color variations which added to the direct color variation accomplished by 70 the rays of light passing through the triangular prisms 5 causing the diaphragm 4 to be highly illuminated in colors which are very beautiful and pleasing to the eye.

We have provided a means for oscillating 75 the diaphragm 4 which comprises a solenoid having the movable core 14 thereof secured to the prisms 5 by means of the studs 15, it being obvious that if the current is intermittently supplied that said solenoid will 80 draw the core 14 in one direction which acting against the spring 16 when the current is released will tend to draw said core in the opposite direction.

In Fig. 4 we have shown the modification 85 of our device in which the lamp 17 is provided to take the place of said electric light globe 1. We have provided a plurality of colored lamps 18 arranged around the lamp 17 causing a similar color effect to the colored 90 reflectors 3 above described. These lamps 18 and the central lamp 17 throw their rays of light toward the diaphragm 19 and triangular prisms similar to the prisms 5 which direct the colored rays of the colored 95 lamps 18 as well as the rays from the lamp 17. The diaphragm 19 as well as the globe or shade 20 entirely surround the lamps 17 and 18 preventing dust from accumulating thereon as well as on the back of the diaphragm.

100 It is obvious that numerous modifications of our device are possible and we do not wish to be limited to the specific construction herein set forth and illustrated in the 105 accompanying drawings but wish to depart from such details as are within the scope of the claim appended hereto.

Having thus described our invention what we claim as new and desire to secure by 110 Letters Patent is:

In an attachment for lamps, a plurality

of divergent colored reflectors, a diaphragm comprising a plurality of triangular prisms hermetically connected to each other and resting against said colored reflectors, means whereby said diaphragm may be detachably secured to said reflectors and a means for oscillating said diaphragm to cause visual changes.

In witness whereof we sign our names in the presence of two subscribing witnesses 10 this 24th day of July 1909.

JUSTUS CORNELIS ZUBLI.
ABRAHAM VLES.
